CLAIM

The ornamental design for a capsule stand, as shown and
described.

DESCRIPTION

FIG. 1 is a front perspective view of a capsule stand
according to the first embodiment of the present invention;
FIG. 2 is a top view thereof;
FIG. 3 is a rear perspective view thereof;
FIG. 4 is a front view thereof;
FIG. 5 is a right side view thereof, with the left side view
being a mirror image thereof;
FIG. 6 is a rear view thereof;
FIG. 7 is a bottom view thereof;
FIG. 8 is a front perspective view of the capsule stand
according to the second embodiment of the present invention;
FIG. 9 is a top view thereof;
FIG. 10 is a rear perspective view thereof;
FIG. 11 is a front view thereof; and
FIG. 12 is a rear view thereof.
